(57) **CLAIM**

The ornamental design for a fence panel, as shown and described.

DESCRIPTION

FIG. 1 is a front view of a fence panel showing my new design;

FIG. 2 is a rear view of the fence panel;

FIG. 3 is a right side view of the fence panel;

FIG. 4 is a left side view of the fence panel;

FIG. 5 is a top view of the fence panel;

FIG. 6 is a bottom view of the fence panel;

FIG. 7 is a top front side perspective exploded view of the fence panel in use; and,

FIG. 8 is a top front side perspective detailed view taken from FIG. 7.

The dot-dot-dash broken line circles in FIGS. 7 and 8 depict the limits of the enlarged/detail view and form no part of the claimed design. The broken lines showing tabs on the fence panels throughout the drawing figures form no part of the claimed design. The broken lines extrinsic to the fence panel shown in FIGS. 7 and 8 are illustrative of environmental structure forming no part of the claimed design.
